UNITED STATES PATENT OFFICE.

ALEXANDER A. HUDSON, OF CINCINNATI, OHIO, ASSIGNOR OF ONE-FOURTH TO
ARTHUR J. UNDERWOOD, OF BELLEVUE, KENTUCKY.

HEEL-BUILDING MACHINE.

Application filed April 16, 1921. Serial No. 461,821.

To all whom it may concern:

Be it known that I, ALEXANDER A. HUDSON, a citizen of the United States of America, and a resident of Cincinnati, in the county of Hamilton and State of Ohio, have invented a new and useful Improvement in a Heel-Building Machine, of which the following is a specification.

This invention relates to heel-building machines and particularly to machines to be used in the building of rough heel blocks from stock leather blanks. Heretofore the manufacture of rough heel blocks has been conducted by the building up of layers of leather in a series of clamps, all of which were hand operated, which travelled about a large wheel or belt and eventually returned to the place of the beginning. During this movement of the wheel, the glue used to secure the blanks would dry, and when the dry rough block turned to the operator, the operator would manually remove the block and then proceed to build a new block and place it in the emptied clamp.

An object of my invention is to provide a device for building rough heel blocks in which the block is automatically secured in the clamps and discharged therefrom.

Another object is to provide means whereby heel blocks can be built more quickly than has been possible heretofore.

Another object is to provide a device for the purposes stated that is simple and efficient in operation.

Another object is to provide a device for the purposes stated, wherein the parts are readily adjustable to permit varying of the pressures exerted upon the heel blocks, and to permit adjustment of the parts to accommodate various sizes and shapes of blocks built thereon.

These and other objects are attained by the means described herein and disclosed in the accompanying drawings, in which:

Fig. 1, is a front elevation of a device embodying my invention.

Fig. 2, is a rear view of parts of the device shown in Fig. 1.

Fig. 3, is a sectional view on line 3—3 of Fig. 1.

Fig. 4, is a plan view of a modified form of a discharge mechanism forming a detail of my invention.

Fig. 5, is an enlarged front view of a clamp forming a detail of my invention.

Fig. 6, is a sectional view on line 6—6 of Fig. 5.

Fig. 7, is an enlarged sectional view taken on line 7—7 of Fig. 6.

My invention comprises a revoluble support d' upon the periphery of which is mounted a series of heel clamps H upon which rough heel blocks K are built up. The support d' is intermittently actuated by means of a motor b^4 adapted to transmit 60 rotatory motion to the support and a suitable means such as the foot lever b^{23} is provided to control the transmission of power from the motor to the support. A cam wheel E is engaged by the yoke h^{14} of the 70 clamps and is adapted to co-operate with certain other mechanisms in automatically moving the yokes into and out of clamping engagement with the heel blocks K .

The frame A has revolubly mounted on 75 it the drive shaft b , by means of suitable brackets a . The shaft b has revolubly mounted on it a worm wheel b' engaging the worm b^2 mounted on the shaft b^3 driven by the motor b^4 . The shaft b^3 is supported 80 by suitable brackets b^5 . A clutch shoe b^6 is mounted on the shaft b and is adapted to revolve with the worm wheel b' . A clutch b^7 is fixedly mounted on the shaft b and has formed within it a bore b^8 parallel with the 85 shaft b . A slot b^{11} extends between the bore b^8 and the outer surface of the clutch. A pin b^9 is reciprocally mounted in the bore b^8 and has extending from it the lug b^{12} extending through the slot b^{11} . A spring b^{10} 90 is mounted in the bore b^8 and tends to move the pin b^9 out of the bore b^8 . The shoe b^6 has a series of notches b^{13} adapted to be moved into registration with the pin b^9 whereby it is possible to transmit motion 95 from the shoe and the worm wheel to the clutch, when the pin b^9 engages in one of the notches b^{13} .

The rod b^{14} is reciprocally mounted upon the brackets b^{15} , which may in turn be 100 mounted upon the brackets b^5 . A spring b^{16} is adapted to yieldingly retain the rod b^{14} in engagement with the clutch b^7 . This is accomplished by securing one end of the spring b^{16} to a bracket b^{15} and securing the 105 other end of the spring to the rod b^{14} . The upper end of the rod b^{14} has a face b^{17} formed thereon and disposed at such an angle that when the lug b^{12} on the pin b^9 engages and is moved over the face b^{17} , the 110

lug b^{12} and the pin b^9 will be moved against the spring b^{10} , whereby the pin b^9 is retained wholly within the body line of the clutch b^7 . A cable b^{22} is secured to the rod b^{14} and is adapted to be actuated by means of a foot lever b^{23} secured upon a platform a^2 forming part of the frame A. The foot lever b^{23} , cable b^{22} and rod b^{14} bear such relation that when the foot lever is depressed, the rod b^{14} is disengaged from the lug b^{12} . The forward end of the drive shaft b is mutilated whereby a lug b^{18} is formed thereon. A collar b^{19} is mounted upon the shaft b adjacent to the forward end thereof, and has a stud b^{20} formed thereon. The forward face b^{21} of the stud b^{20} is spaced from and does not engage the support d' .

A driven shaft d is revolvably mounted upon the frame A and has mounted upon its forward end a support d' . The support as shown herein is circular in form. A gear d^2 is mounted upon the shaft d and is adapted to transmit rotatory motion to the support d' . The gear d^2 has a series of alternating deep and shallow notches d^3 and d^4 respectively. The notches d^3 and d^4 are spaced by the faces d^5 formed on the gear. The stud b^{21} formed on the sleeve b^{19} is adapted to engage in the deep notches d^3 and the lug b^{18} formed on the shaft b is adapted to engage in the shallow notches d^4 .

A stationary cam wheel E is mounted upon the frame A adjacent the support d' . The locking cam e is mounted upon the cam wheel E and has a ledge e^7 having a cam face e' eccentric to the shaft d and the support d' . The forward or upper end e^2 of the ledge formed on the locking cam is formed into a shoulder e^3 extending away from the shaft d . The locking cam is adjustably secured upon the cam wheel E by any suitable means such as being bolted upon the cam wheel, the bolts e^{14} passing through slots e^8 in the locking cam. A discharge spring e^4 is mounted upon cam wheel E on the side opposite the locking cam on approximately the same level with the locking cam. A disc e^5 is mounted on cam wheel E in alignment with the spring e^4 and the shaft d . The purposes of these elements will be more fully explained hereafter. The outer edge or periphery of the cam wheel E has formed on it a way or track e^6 that is engaged by the clamps H. At the top of the cam wheel E the track e^6 extends away from the support d' for a reason that will be explained hereafter.

An unlocking cam F is mounted upon cam wheel E adjacent to the spring e^4 , and has a lug f formed thereon. The upper or cam face f' of the lug f is adapted to engage the clamps and to unlock them in a manner that will be explained hereafter. The lug f extends upwardly on a line substan-

tially tangential to the periphery of the cam wheel E.

A U-shaped bracket G is mounted upon the cam wheel E and has an arm g extending over the unlocking cam F. The bracket G is positioned intermediate the spring e^4 and cam F. The forward branch g' of the bracket G has extending from it, the guide arm g^3 adapted to engage the forward or front side of the clamps as they pass by and to retain the clamps in engagement with the track e^6 . It is at this place that the upper end of the track extends away from the support d' . The branches of the U-shaped bracket are so disposed that part of the clamps will pass between them.

Each clamp H comprises a base h upon which is pivotally mounted one end of a bottom plate h' , by means of pivot h^{21} . A transverse cam shaft h^2 is mounted revolvably upon the base and has formed upon it a cam h^3 adapted to engage the plate h' and to adjustably retain the plate at a determinable inclination to base h . A bolt h^6 extends reciprocally through the bores h^7 in the plate, h^5 in the base h , and d^6 in the support d' . The bore h^7 is countersunk as shown at h^4 and is adapted to accommodate a head h^{45} formed on one end of the bolt and which normally engages the plate h' . A head h^8 formed on the other end of the bolt is adapted to engage the disc e^5 . A spring h^9 mounted upon the bolt engages the head h^8 and the support d' , and yieldingly retains the head h^{45} in engagement with the plate h' . Adjustable rods h^{10} are mounted upon the base h and extend upwardly from the base adjacent the free end of the plate h' . These rods are connected at their tops by bar h^{48} having a lip h^{49} under which the heel blanks are inserted as the heel block is built up. The lip retains the blanks upon one another until the clamp secures the heel block. The rods serve as an abutment for the forward ends of the heel blanks and also as a gage for the guidance of an employee in building up heel blocks. The cam shaft h^2 has an apron h^{13} formed thereon adapted to lie upon the side of the base. The apron has a slot h^{12} concentric with the shaft h^2 . A bolt h^{11} extends thru the slot h^{12} and engages in a threaded way formed in the base. The head of the bolt h^{11} is adapted to engage and lock or clamp the apron upon the base, whereby the cam shaft may be secured in an adjusted position. The base is secured upon the support d' by any suitable means such as bolts h^{47} . A yoke h^{14} has its branches h^{17} and h^{18} pivotally mounted upon the ends of the base h by means of the adjustable bearings or pivots h^{15} and h^{16} respectively. The pivots h^{15} and h^{16} engage in the bores h^{20} and h^{21} respectively in the base h . A bore h^{211} parallel with the branches h^{17} and

h¹⁸ extends thru the body *h⁴⁶* of the yoke and in this bore is slidably mounted a sleeve *h²²* having within it a threaded way in which an adjustable screw *h²³* engages. A top plate *h²⁴* is mounted upon the lower end of the screw *h²³* by means of a pivot *h²⁵*. A U-shaped clip *h⁴⁵* is removably mounted upon one end of the top plate *h²⁴*, extends slidably about the branch *h¹⁸* and serves to prevent rotation of the top plate and the screw *h²³*. The lugs *h²⁶* formed on the yoke body *h⁴⁶* extend from the yoke body in a direction opposite to the branches *h¹⁷* and *h¹⁸*. The bore *h²¹* in the yoke registers with the space between the lugs *h²⁶*. A transverse slot *h²⁷* is formed in each lug, these slots registering with the space between the lugs and being in alignment with one another. A pin *h²⁸* is reciprocally mounted in the slots *h²⁷* and extends thru the arms *h³²* and *h³³* formed upon the upper end of the sleeve *h²²*. A spring *h²⁹* is disposed about the upper end of the sleeve *h²²* and one end thereof is secured upon the pin *h²⁸*, and the other end thereof abuts the yoke body *h⁴⁶*. A roller *h³⁰* is mounted upon the pin *h²⁸* intermediate the arms *h³²* and *h³³*. A shaft *h³⁴* is mounted upon the upper end of the lugs *h²⁶*, and has rotatively mounted upon it, intermediate the lugs, a lever arm *h³⁵*. The lever arm has a cam face *h³⁶* formed thereon, which face terminates at the shoulders *h³⁷* and *h³⁸* formed on the lever arm. The shoulders are adapted to engage the roller *h³⁰* and to thereby limit the movement of the lever arm. A roller *h³⁹* is mounted upon the shaft *h⁴⁰* mounted on the free and bifurcated end of the lever arm. The shaft *h⁴⁰* extends beyond the lever arm as shown in Fig. 6, for a purpose which will be explained hereafter. Lugs *h⁴¹* and *h⁴²* are formed on the rear of the yoke body and have disposed between them a roller *h⁴⁴* revolvably mounted upon a shaft *h⁴³* extending thru the lugs *h⁴¹* and *h⁴²*.

The operation of my device is as follows: The operator takes his position upon the platform *a²* and builds a rough block *K* upon the bottom plate *h'* when a given clamp *H* is in the position shown as *X*, Fig. 1. In this position the yoke extends from the base in such direction that the branches assume a substantially horizontal position.

After the operator has built block *K* upon the clamp in position *X*, by placing glue on several leather blanks and mounting the blanks on one another, he operates the foot lever *b²³*, thereby disengaging the lug *b¹²* and the rod *b¹⁴*, whereupon the spring *b¹⁰* causes the pin *b⁹* to engage in one of the slots *h¹³* in the clutch shoe *b⁶*. The shaft *b* and the sleeve *b¹⁹* are therefore rotatively actuated by the worm wheel *b'*. The stud *b²⁰* engages the gear *d²* and moves same, see Fig. 1, in a counter clockwise direction. The mutilated end of the shaft *b* permits the faces *d³* on the gear to pass the shaft *b*, and when the next shallow notch registers with the shaft *b*, the mutilated end or lug *b¹⁸* enters in the shallow notch and secures the gear against further motion. During this time the clutch *b⁷* has made one complete revolution and providing the operator has released the foot lever *b²³*, the rod *b¹⁴* will engage the lug *b¹²* and thereby disengage the pin *b⁹* from the clutch shoe *b⁶*. This movement of the gear is sufficient to advance the clamp shown at *Y*, Fig. 1, to the position *X*.

The roller *h⁴⁴* engages the track *e⁶* on the cam wheel *E*, and as the clamps are moved towards the locking cam *e*, the yokes of the clamps are moved to positions so that the top plates *h²⁴* are disposed over and above the rough heel blocks *K*. When in this position the roller *h³⁹* on the lever arm *h³⁵* engages the shoulder *e⁸* formed on the ledge *e⁷* on the locking cam. As the roller passes over the locking cam, the roller is moved towards the shaft *d*, whereby the cam face *h³⁶* on the lever arm *h³⁵* is moved over the roller *h³⁰* mounted on the sleeve *h²²*, thereby causing the top plate *h²⁴* to be moved upon and clamped upon the rough heel block *K*, and tensioning spring *h²⁹*. When the roller *h³⁰* engages the shoulder *h²⁸*, the lever arm is locked upon the yoke. The heel block is retained under pressure in this clamped position until the clamp has moved to a position wherein the shaft *h⁴⁰* engages the unlocking cam *F*. The rough shoe block is gradually released from the pressure exerted thereon by the clamp when the shaft *h⁴⁰* engages the cam face *f'* which serves to move the roller *h³⁹* away from the shaft *d*, whereupon the roller engages the arm *g*, mounted on bracket *G*. The arm *g* is so formed that the roller is gradually extended. The spring *h²⁹* retains the roller in engagement with the arm *g*, wherefore the pressure on the heel block is gradually decreased. By the time that the clamp reaches the position *Z*, the lever arm has been fully extended and the heel block is ready to be discharged from the clamp. At this time the head *h⁸* of the bolt *h⁵* engages the disc *e⁵* and the head *h⁴⁵* thereof is projected from the bore in the bottom plate *h'*, and unseats the block *K* from the bottom plate *h'*. At approximately this time the spring *e⁴* engages the rear of the block *K*, and between the spring *e⁴* and the bolt *h⁸*, the block *K* is ejected forwardly from the clamp and falls into a suitable container provided therefor. At about this time the guide arm *g³* engages the forward lug *h²⁶* formed on the yoke and serves to retain the roller *h⁴⁴* on the yoke track *e⁶*, which at this place extends rearwardly from the support *d'*, wherefore the yoke and the branches move about pivots *h¹⁵* and *h¹⁶*, whereupon the yoke is moved by gravity to such a position.

tion that the branches are in a substantially horizontal position, whereupon the operator can build up another heel upon the empty clamp.

5 The adjustable rods h^{10} serve as a gage or guide whereby the operator can determine the height to which he should build up a heel block. A suitable stand A' is constructed above the support d' and upon 10 which the heel blanks or lifts may be disposed. The heel lifts are glued at the time that they are placed upon the bottom plate h' by the operator, and when they are discharged they have dried. The lip h^{49} on the bar h^{48} mounted on the gage rods serves as a retaining means under which the heel blanks are retained until the top plate 15 clamps the heel block. A check h^{50} may be mounted adjustably upon the base a so that 20 it will extend over the bottom plate and serves as an abutment for the lowermost heel blank to prevent slippage or movement of the lowermost heel blank while the heel block is being built up.

25 The knock out mechanism M disclosed in Fig. 4 may be employed to supersede the spring e^4 and perform the function thereof. The mechanism comprises a rod m pivotally mounted intermediate its ends upon the 30 frame A by means of a pivot m' , the rod having an angular face m^2 on one end adapted to be engaged by the block m^3 mounted on the clutch b^7 and to be moved thereby against the yielding resistance of spring 35 m^4 mounted at one end on frame A and at its other end upon the rod m . A reciprocating arm m^5 is pivotally mounted at one of its ends upon the other end of the rod and extends intermediate its ends thru the 40 frame A at approximately the place where the spring e^4 is mounted (see Fig. 1). A head m^6 is mounted on the free end of the arm and is adapted to be moved into engagement with a heel block K when a clamp 45 assumes the position Z , thereby ejecting the heel block from the clamp. The arm m^5 extends reciprocally through a sleeve m^7 mounted on the frame, the sleeve serving as a stop determining the forward limit to 50 which the head m^6 may be moved. This limit is such that the head m^6 will not interfere with the movement of clamps.

What I claim is:

55 1. In a heel building machine the combination of a cam wheel, a track on the cam wheel, a revoluble support mounted adjacent the cam wheel, clamps mounted on the support adapted to receive heel blocks and comprising a base, a yoke pivotally mounted on the base and engaging the track whereby the yoke is alternately moved to and from an operative position over the base, means on the 60 yoke adapted to be moved into clamping engagement upon a heel block when the yoke is in an operative position, a locking cam mounted adjacent the support adapted to move the last mentioned means into clamping engagement upon a heel block.

ing cam mounted adjacent the support adapted to move the last mentioned means into clamping engagement upon a heel block.

2. In a heel building machine the combination of a cam wheel, a track on the cam wheel, a revoluble support mounted adjacent the cam wheel, clamps mounted on the support adapted to receive heel blocks and comprising a base, a yoke pivotally mounted on the base and engaging the track whereby the yoke is alternately moved to and from an operative position over the base, means on the yoke adapted to be moved into clamping engagement upon a heel block when the yoke is in an operative position, a locking cam mounted adjacent the support adapted to move the last mentioned means into clamping engagement upon a heel block, and an unlocking cam mounted adjacent the support adapted to move said last mentioned means from clamping engagement upon a heel block.

3. In a heel building machine the combination of a cam wheel, a track on the cam wheel, a revoluble support mounted adjacent the cam wheel, clamps mounted on the support adapted to receive heel blocks and comprising a base, a yoke pivotally mounted on the base and engaging the track whereby the yoke is alternately moved to and from an operative position over the base, means on the yoke adapted to be moved into clamping engagement upon a heel block when the yoke is in an operative position, a locking cam mounted adjacent the support adapted to move the last mentioned means into clamping engagement upon a heel block, an unlocking cam mounted adjacent the support adapted to move said last mentioned means from clamping engagement upon a heel block a bolt mounted reciprocally upon the base adapted to separate a heel block from the base, and means adapted to actuate the bolt upon the release of the heel block from the clamping means.

4. In a heel building machine the combination of a cam wheel, a track on the cam wheel, a revoluble support mounted adjacent the cam wheel, clamps mounted on the support adapted to receive heel blocks and comprising a base, a yoke pivotally mounted on the base and engaging the track whereby the yoke is alternately moved to and from an operative position over the base, means on the yoke adapted to be moved into clamping engagement upon a heel block when the yoke is in an operative position, a locking cam mounted adjacent the support adapted to move the last mentioned means into clamping engagement upon a heel block, an unlocking cam mounted adjacent the support adapted to move said last mentioned means from clamping engagement upon a heel block, a bolt mounted reciprocally upon the base adapted to separate a heel block from

- the base, means adapted to actuate the bolt upon the release of the heel block from the clamping means, and a knock-out device adapted to co-operate with the bolt whereby a heel block is ejected from the base.
5. In a heel building machine, the combination of a vertical cam wheel, a track on the cam wheel, a revoluble support mounted vertically adjacent the cam wheel, the cam wheel and track thereon extending away from the top of the support, clamps mounted on the support adapted to receive heel blocks and comprising a base, a yoke pivotally mounted on the base, a roller mounted on the yoke and engaging the track, means to retain the roller upon the track, the engagement of the roller with the portion of the track extending from the support serving to permit movement of the yoke upon the base whereby the yoke assumes an inoperative position as the clamp moves towards the top of the support, and is moved towards an operative position as the clamp moves from the top of the support, means mounted on the yoke adapted to clamp a heel block upon the base when the yoke is in an operative position, means to move the clamping means upon a heel block, means to release a heel block from the clamping means, and means adapted to intermittently actuate the support.
6. In a heel building machine the combination of a cam wheel, a track on the cam wheel, a revoluble support mounted adjacent the cam wheel, clamps mounted on the support adapted to receive heel blocks and comprising a base, a yoke pivotally mounted on the base and engaging the track whereby the yoke is alternately moved to and from an operative position over the base, the yoke having a bore in substantial parallelism with its branches, a sleeve mounted reciprocally in the bore, means yieldingly resisting movement of the sleeve towards the base, a screw mounted adjustably upon the sleeve, a plate mounted upon the screw adapted to engage a heel block mounted upon the base, a lever mounted upon the yoke and engaging the sleeve and controlling the movement of the sleeve, a locking cam mounted adjacent the support adapted to engage the lever whereby the plate is moved towards the base, means to lock the lever and plate at the end of their movements towards the base, an unlocking cam adapted to unlock the lever and the plate, an arm mounted adjacent the unlocking cam adapted to engage the lever and to permit gradual movement of the plate from the base, means to eject a heel block from the base when the plate has reached the end of its movement away from the base, and means to intermittently actuate the support.
7. A clamp comprising a base, a bottom plate pivotally mounted on the base adapted to receive a heel block, means to adjustably incline the bottom plate over the base, a yoke pivotally mounted on the base adapted in an operative position to extend over the bottom plate and in its inoperative position to assume a position to the side of the bottom plate, a top plate mounted reciprocally on the yoke, and means to clamp the top plate upon the heel block when the yoke is in an operative position.
8. A clamp comprising a base, a plate pivotally mounted on the base adapted to receive a heel block, means to adjustably incline the plate over the base, a yoke pivotally mounted on the base adapted in an operative position to extend over the plate and in its inoperative position to assume a position to the side of the plate, means mounted on the yoke adapted in the operative position of the yoke to clamp a heel block upon the plate and means adapted to eject a heel block from the plate when the yoke is in an inoperative position.
9. A clamp for building heel blocks comprising a base, a yoke the branches of which are pivotally mounted on the base and having a bore in substantial parallelism with the branches, a sleeve mounted reciprocally in the bore, a plate mounted on the sleeve intermediate the branches, a lever mounted on the yoke, means yieldingly retaining the sleeve in engagement with the lever, the lever and sleeve being adapted to interlock, whereby the plate is moved and locked into clamping engagement upon a heel block, and a roller mounted on the lever adapted to engage a cam adapted to interlock the lever and the sleeve.
10. A clamp for building heel blocks comprising a base, a yoke the branches of which are pivotally mounted on the base and having a bore in substantial parallelism with the branches, a sleeve mounted reciprocally in the bore, a plate mounted on the sleeve intermediate the branches, a lever mounted on the yoke, means yieldingly retaining the sleeve in engagement with the lever, the lever and sleeve being adapted to interlock, whereby the plate is moved and locked into clamping engagement upon a heel block, a roller mounted on the lever adapted to engage a cam adapted to interlock the lever and the sleeve, and a shaft extending from the lever adapted to engage a cam adapted to unlock the lever and sleeve whereby the heel block may be removed from the base.
11. A clamp for building heel blocks comprising a base, a yoke the branches of which are pivotally mounted on the base and having a bore in substantial parallelism with the branches, a sleeve mounted reciprocally in the bore, a plate mounted on the sleeve intermediate the branches, a lever mounted on the yoke, means yieldingly retaining the sleeve in engagement with the lever, the

- lever and sleeve being adapted to interlock, whereby the plate is moved and locked into clamping engagement upon a heel block, a roller mounted on the lever adapted to engage a cam adapted to interlock the lever and the sleeve, a shaft extending from the lever adapted to engage a cam adapted to unlock the lever and sleeve, whereby the heel block may be removed from the base, 5 a bolt mounted reciprocally on the base, a head on the bolt adapted to eject a heel block from the clamp, and means yieldingly retaining the head on the base whereby a heel block may be built thereover.
- 10 12. A clamp for building heel blocks comprising a base having a bore, a yoke, branches on the yoke, pivots connecting the branches and the base, the yoke having a bore substantially parallel with the branches, a sleeve mounted reciprocally in the bore in the yoke, a screw mounted adjustably in the sleeve and extending between the branches in substantial parallelism therewith, a plate mounted on the screw, 15 a clip mounted removably on the plate and slidably engaging one of the branches, a roller mounted on the sleeve, a normally extended lever pivotally mounted on the yoke engaging the roller, a spring yieldably retaining the roller in engagement with the lever, a roller mounted on the lever adapted to engage a locking cam adapted to move the lever to a contracted position, and to engage an arm adapted to permit gradual 20 movement of the lever to an extended position, means to interlock the lever and roller when the lever is moved to a contracted position, a shaft extending from the lever adapted to engage an unlocking cam whereby the roller and lever are unlocked and the lever is gradually extended, the plate and base being adapted to have a heel block clamped between one another when the lever is moved to a contracted position, and a bolt 25 mounted reciprocally in the bore in the base adapted to discharge a heel block from the base when the lever is extended.
13. A clamp for building heel blocks comprising a base adapted to receive a heel block, a yoke pivotally mounted on the base, means mounted on the yoke adapted to be moved into clamping engagement upon a heel block, and an adjustable gage mounted on the base adapted to serve as a guide and as 30 a brace against which the heel blanks are nested when being assembled into a heel block, the gage being provided with a lip extending over the base, between which lip and base the heel blanks are nested.
14. In a heel building machine the combination of a cam wheel, a track on the cam wheel, a revolute support mounted adjacent the cam wheel, clamps mounted on the support adapted to receive heel blocks and comprising a base, a yoke pivotally 35 mounted on the base and engaging the track whereby the yoke is alternately moved to and from an operative position over the base, means on the yoke adapted to be moved into clamping engagement upon a heel block when the yoke is in an operative position, a locking cam mounted adjacent the support adapted to move the last mentioned means into clamping engagement upon a heel block, an unlocking cam mounted adjacent the support adapted to move the last mentioned means from clamping engagement upon a heel block, and reciprocating means adapted to separate a heel block from the base upon the release of the 40 heel block from the clamping means.
15. In a heel building machine the combination of a cam wheel, a track on the cam wheel, a revolute support mounted adjacent the cam wheel, clamps mounted on the support adapted to receive heel blocks and comprising a base, a yoke pivotally mounted on the base and engaging the track whereby the yoke is alternately moved to and from an operative position over the base, means on the yoke adapted to be moved into clamping engagement upon a heel block when the yoke is in an operative position, a locking cam mounted adjacent the support adapted to move the last mentioned means into clamping engagement upon a heel block, an unlocking cam mounted adjacent the support adapted to move the last mentioned means from clamping engagement upon a heel block, and a knock out mechanism adapted to separate a heel block from the base upon the release of the heel block from the clamping means.
16. A clamp for building heel blocks comprising a base, a plate pivotally mounted at one end on the base, a cam revolvably mounted on the base adapted to engage the plate and to move the plate about its pivoted mounting, and means to clamp a heel block upon the plate.
17. A clamp for building heel blocks comprising a base, a plate mounted pivotally upon the base, a cam revolvably mounted on the base adapted to engage the plate and to move the plate about its pivoted mounting, means to lock the cam upon the base, and means to clamp a heel block upon the plate.
18. A clamp for building heel blocks comprising a base, a plate mounted pivotally upon the base, a cam revolvably mounted on the base adapted to engage the plate and to move the plate about its pivoted mounting, means to lock the cam upon the base, means to clamp a heel block upon the plate, and a check adapted to preclude slipping of the heel on the plate.
- In testimony whereof I have hereunto subscribed my name this 13th day of April, 1921.
- ALEXANDER A. HUDSON.
